United States Patent Office

Des. 224,666
Patented Aug. 22, 1972

224,666

POSTAGE METER

Robert E. Schmeck, Old Greenwich, and Einar W. Tanguard, Norwalk, Conn., assignors to Pitney-Bowes, Inc., Stamford, Conn.

Filed Jan. 19, 1971, Ser. No. 107,875

Term of patent 14 years

Int. Cl. D18—02

U.S. Cl. D64—11

FIG. 2

FIG. 3

FIG. 4

FIG. 5

FIG. 6

FIG. 1 is a perspective view of a postage meter embodying our new design;

FIG. 2 is a front elevational view of said postage meter;
FIG. 3 is a top plan view of said postage meter;
FIG. 4 is a side elevational view of said postage meter;
FIG. 5 is a rear elevational view of said postage meter;
FIG. 6 is a bottom view of said postage meter.

We claim:

The ornamental design for a postage meter, substantially as shown.
